JONATHAN CRABTREE, OF PHILADELPHIA, PENNSYLVANIA.

Design No. 4,448, dated November 1, 1870.

DESIGN FOR A CARPET-PATTERN.

The Schedule referred to in these Letters Patent and making part of the same.

I, JONATHAN CRABTREE, of the city and county of Philadelphia and State of Pennsylvania, have invented and produced a new and original Design for Carpets, of which the following is a specification.

The nature of my design is fully represented in the accompanying photographic illustration, to which reference is made.

I claim as my invention—
The design for a carpet, as shown.
Philadelphia, September 23, 1870.
